SPOUT

Donald M. Genaro, Haworth, N.J., and Charles W. Pelly,
Scarsdale, N.Y., assignors to American Standard Inc.,
New York, N.Y.

Filed Mar. 6, 1972, Ser. No. 232,358

Term of patent 14 years

Int. Cl. D23—01

U.S. Cl. D23—32

FIG. 1

FIG. 2

FIG. 3

FIG. 1 is a front elevational view of a spout embodying my new design;

FIG. 2 is a side elevational view thereof; and

FIG. 3 is a top plan view thereof with a portion broken away for convenience of illustration.

I claim:

The ornamental design for a spout, substantially as shown.
